PLEATED PROTECTIVE SHIELD

Ugo Torricelli, New York, N. Y., assignor to Torricelli Creations, Incorporated, New York, N. Y., a corporation of New York

Application December 29, 1951, Serial No. 264,139

4 Claims. (Cl. 2-174)

1

This invention relates to a pleated protective shield composed of sheet material and especially designed and adapted for use as a beauty parlor accessory to protect the face, neck and ears of the wearer during hair drying and related procedures in which hot air is directed against the hair by means of a hair dryer or hot-air blower.

In my co-pending application Ser. No. 200,787, filed December 14, 1950, now Patent No. 2,619,646, I have described and claimed a protective shield of the same general character as that here involved but in connection therewith I have now discovered that the usefulness, effectiveness and durability of such a shield can be improved and prolonged by certain improvements thereto which form the subject-matter of this application. While the protective shield of my aforesaid co-pending application is well adapted to serve the purpose for which it was intended, the construction of the shield herein-disclosed provides substantially increased strength, efficiency, durability and ease of manipulation.

My improved protective shield construction is illustrated in the accompanying drawing, in which:

Fig. 1 is a plan view of the prepared sheet material blank and associated tie element embodying my new improvements;

Fig. 2 is a plan view illustrating my present protective shield in the expanded circular form as it appears during use;

Fig. 3 is a perspective view of the pleated sheet material in its retracted condition illustrating how it is formed into a compact package;

Fig. 4 is a side elevational view of my new protective shield in its expanded condition and applied to the head of the wearer;

Fig. 5 is a somewhat diagrammatic side elevational view to illustrate the angular relationship of the pleats with respect to the tabs forming the inner periphery of the expanded shield when applied to the head of the wearer;

Fig. 6 is a fragmentary perspective view of the pleated shield showing how the tabs are related and overlapped and

Fig. 7 is a perspective view illustrating a typical clamp or other holding device applicable to the ends of the tie element of the shield for holding the shield in position on the head of the wearer while at the same time permitting accommodation of the shield to heads of different sizes.

Referring now to the drawing in detail, a strip of sheet material 10, of uniform or substantially

uniform width from end to end, is folded upon itself or pleated in the manner illustrated to provide a multiplicity of individual pleats 11, each of which is provided with a hole or aperture 12 therethrough. It will be particularly noted that the holes or apertures 12 are located and arranged in pairs and that each pair of such holes or apertures is closely adjacent the fold line 13 between the successive pairs of individual pleats 11 and that the spacing between successive pairs of holes or apertures is thus nearly equal to the width of two such pleats or folds. This I have found to be highly advantageous not only because it enables the tie cord to be threaded through the holes more quickly and simply but because the shield is stronger and has greater ease of manipulation with respect to retracting and expanding the pleated sheet material into the compact package shown in Fig. 3 and the expanded condition during use as shown in Fig. 2, respectively. Thus, from Fig. 1, in particular, it will be observed that the first pair of holes or apertures is arranged on either side of the first fold line 13 and close to such fold line, that the second fold line has no contiguous holes or apertures, that the third fold line is provided with the contiguous holes or apertures like those of the first fold line and that this arrangement of fold lines and holes or apertures is repeated serially throughout the length of the strip of sheet material. As also shown in Fig. 1, the tie element 14 can be quickly and readily threaded through such pairs of holes or apertures and that those portions of the tie cord intermediate succeeding pairs of holes or apertures lie on and extend over unapertured sheet material, thus providing an improved construction of superior strength.

Each individual pleat 11 terminates at one end in a projecting tab 15, the sheet material between successive tabs having been notched out or cut away as indicated at 16 so as to provide individual semi-detached tabs each of which has a considerable freedom of movement with respect to the pleat from which it extends or projects as well as having facile movement with respect to the adjacent and succeeding tabs during the retracting of the pleated sheet material to the compact package form and the expanding of the same to the extended form which it occupies during use.

Particular attention is directed to the fact that the tabs 15 are bendable with respect to the pleats 11 from which they extend and that such bendability takes place along an angularly trans-

verse line or fold which, in contrast to the tabs in my aforesaid co-pending application, is at an angle to the pleats which is not a right angle. This is indicated in Fig. 1 by the dotted lines 17 which constitute the lines of folding or bendability of the tabs and which, as will be readily perceived, are arranged in pairs such that the lines of fold or bendability of each pair of tabs form a shallow V, apex downward, the notched-out portions 16 of the strips tapering toward and terminating at the V-apices. Consequently, when each tab is bent about its angularly disposed fold-line, it assumes a position with respect to its pleat which is not a right angle and alternate tabs become similarly bent thus forming two differently directed series of tabs (see Fig. 6) and when the sheet material is in its pleated condition, the successive tabs appreciably overlap to form, in effect, a continuous inner surface wherein each of the tabs freely slides upon the preceding and succeeding tabs while still remaining overlapped. Thus, the tabs not only overlap but overlap in such a manner that in all positions of the shield they provide the said continuous surface, whereby the expanded shield when applied to the head of the wearer is exceptionally comfortable and has added strength and rigidity for enhancing the effectiveness thereof and for resisting the downward pressure which is exerted thereon by the hot-air blasts from the hair dryer or other blowing device.

These results are even more pronounced due to the fact that, as best shown in Fig. 1, the pleats 11 and tabs 15 do not form a right angle with one another but the pleats form an acute (less than 90°) angle with the tabs and the leverage due to the length of the pleats and the force of the hot-air blasts contacting the same is such as to provide exceptional and unusual strength since the tendency of the outer portion of the pleats to move downwardly under pressure does not strongly tend to pull the inner surface of the shield formed by the folded tabs away from the head of the wearer but exerts the contrary effect of tending to press the tabs more firmly against the wearer's head. Thus, there is little or no likelihood of the shield's slipping down the head of the wearer or of being forced into uneven or uncomfortable contact with the head, thereby providing a superior protective shield which has increased strength, rigidity and durability as well as superior effectiveness for the intended purpose.

The strip of sheet material may be composed of any suitable or desirable material or composition, such as paper or a thin synthetic plastic which has sufficient strength to be self-supporting and which is adapted to be pleated, retracted and expanded without cracking or otherwise rupturing and which has sufficient flexibility coupled with adequate supporting rigidity to make it possible to retract and expand the pleats easily and without deformation. The strip may be colored or uncolored; decorated or plain. While in one form of the invention the sheet material may be an inexpensive material, such as paper, which can, if desired, be discarded after a single use thereof, it is also within the purview of the invention to make the protective shield of more durable material, like a plastic, which is capable of being sterilized so that it can be used over and over again and for successive hair drying or related procedures. In its retracted condition, the pleated strip material forms a very compact package for shipping, storing and other

purposes or for being carried in a lady's handbag or pocketbook in the event that it is desired by any particular person to bring her own protective shield to the beauty parlor or hairdressing establishment. It is retained in the retracted position, until used, by an envelope, rubber band, cord or other holding instrumentality.

The tie element 14 may be made of any suitable cellulosic or non-cellulosic material, such 10 as a suitable cord or string, but may equally well be made of any flexible composition or synthetic material the specific nature of which does not constitute a limitation upon the invention. The tie element has adequate flexibility so that it 15 can be threaded through the pairs of apertures referred to above and so that it can be tied at the back of the wearer's head, but in this connection I have found it preferable to provide a clamp for holding the ends of the tie element 20 without the necessity for knotting and unknotting the same and so as to permit ready adjustment with respect to the tightness of the shield about the wearer's head and to allow for the application of the shield to heads of different 25 sizes. An exemplary clamp is illustrated at 18 in Fig. 7 but it is to be understood that any suitable simple clamp may be employed and that the specific nature or construction of such clamp does not per se form a part of or a limitation upon 30 the invention. The clamp is of any type capable of holding the tie element in adjusted position while enabling such element to be tightened or slackened by pulling on the same.

It will thus be apparent that I have provided 35 a superior and improved protective shield for beauty parlor and related procedures whether carried out at a hair-dressing establishment or at home and that such protective shield has a unique construction with greatly enhanced utility and 40 effectiveness. The shield is simple and inexpensive in its construction and is easily and simply converted from its retracted to its expanded condition, or vice versa.

The foregoing is intended as illustrative and not 45 as restrictive since, within the terms of the appended claims, various modifications may be made without departing from the invention.

I claim:

1. A pleated protective shield adapted to be 50 retracted into a compact package and to be expanded into circular form for application about the head of a wearer, which comprises a strip of sheet material of uniform width from end to end and folded upon itself a plurality of times to provide a series of individual pleats, a tab projecting from one end of each such pleat and bendable with respect to its pleat at an angle other than a right angle, succeeding tabs being separated by notches in the sheet material and each such pleat being provided with a hole adjacent one side of the 55 pleat and near the tab thereof and a tie element threaded through said holes and adapted to be secured at the back of the head of the wearer.

2. A pleated protective shield adapted to be 60 retracted into a compact package and to be expanded into circular form for application about the head of a wearer, which comprises a strip of sheet material of uniform width from end to end and folded upon itself a plurality of times to provide a series of individual pleats, a tab projecting from one end of each such pleat and bendable with respect to its pleat at an angle other than a right angle, succeeding tabs being separated by notches 65 in the sheet material and each such pleat being provided with a hole adjacent one side of the 70

75

pleat and near the tab thereof and a tie element threaded through said holes and adapted to be secured at the back of the head of the wearer, the said holes being arranged in closely adjacent pairs and the spacing between succeeding pairs of holes being nearly equal to the width of two such pleats.

3. A pleated protective shield adapted to be retracted into a compact package and to be expanded into circular form for application about the head of a wearer, which comprises a strip of sheet material of uniform width from end to end and folded upon itself a plurality of times to provide a series of individual pleats, a tab projecting from one end of each such pleat and bendable with respect to its pleat at an angle other than a right angle, succeeding tabs being separated by V-shaped notches in the sheet material along one edge and having their apices terminating at the junctures of the tabs and pleats and each such pleat being provided with a hole adjacent one side of the pleat and near the tab thereof and a tie element threaded through said holes and adapted to be secured at the back of the head of the wearer, adjacent pairs of tabs being bendable at angles to one another which converge toward the fold-lines between alternate pairs of pleats, thereby forming a series of shallow V's with their apices downward, such apices being substantially coterminous with the apices of the aforesaid V-shaped notches of the sheet material.

4. A pleated paper protective shield adapted to be secured about the head of a wearer to prevent hot-air blasts from a hair dryer or the like from making contact with the face, neck and ears of the

5

10

15

20

25

30

35

wearer, which comprises a strip of sheet material of substantially uniform width from end to end folded upon itself to provide a multiplicity of pleats, a tab extending from one end of the same end of each such pleat and bendable at an angle other than a right angle with respect to its pleat, the sheet material being notched out between successive tabs to provide freedom of movement of each such tab and the series of tabs in their bent condition being in overlapping relationship so as to provide a continuous inner surface adapted to make contact with the head of the wearer and a tie element threaded through closely adjacent pairs of holes provided in succeeding pairs of pleats, the protective shield when in its expanded condition and applied to the head of the wearer being disposed so that the pleats extend from the continuous surface formed by the succession of tabs at an angle less than a right angle.
